FIG. 3.

FIG. 4

INVENTOR:
Arthur H. Ballard
By *Cooper & Maynard*
ATTORNEYS:

UNITED STATES PATENT OFFICE.

ARTHUR H. BALLARD, OF BOSTON, MASSACHUSETTS.

WINDOW.

Application filed April 5, 1921. Serial No. 458,728.

To all whom it may concern:

Be it known that I, ARTHUR H. BALLARD, of Boston, in the county of Suffolk and State of Massachusetts, a citizen of the United

5 States, have invented a new and useful Improvement in Windows, of which the following is a full, clear, and exact description, reference being had to the accompanying drawings, forming a part of this specification, in explaining its nature.

10 The present invention relates to an improvement in windows and essentially to a car window or one having a single sliding sash.

15 The object of my invention is particularly to provide for an airtight closure of the window when the sash is occupying a closed position and at the same time to permit of an easy opening and closing of the sash.

20 The invention can best be seen and understood by reference to the drawings, in which—

Figure 1 is a front elevation of a window.

Fig. 2 is a section on the line 2—2 of 25 Fig. 1.

Fig. 3 is a section on the line 3—3 of Fig. 1.

Fig. 4 is the same as Fig. 3 except that the sash is shown occupying a sealed position as will later be explained.

30 Referring to the drawings:—

1 represents the frame and 2 the sash. The frame comprises a head portion 3, side portions or jambs 4, 4 and a sill 5. The 35 side portions of the frame are provided with the usual channels or runways 6 within which the side bars of the sash are contained and in which the sash is slideable to extend upwardly through an opening 7 in the head 40 of the frame when occupying an open position. On the sill just outside the lower sash bar is a weather-strip 8.

When the sash is occupying a closed position the side bars thereof will be contained 45 in the runways of the frame, the top bar of the sash within the lower part of the opening 7 in the head of the frame and the lower sash bar between the weather-strip 8 and the facing 9 of the sill. When thus contained the sash is capable of being appreciably moved translatable as a whole in or out in a direction perpendicular to the 50 plane of the sash, the width of the runways

6, and the width of the lower portion of the opening 7 and the distance between the 55 weather-strip 8 and facing 9 of the sill permitting of such movement.

The runways 6 are provided each with a U-shaped channel bar 10 preferably of metal. These channel bars move translatable with 60 the sash, but are fixed against endwise displacement as will later be explained, the sash only being slideable. The sash slides within the channel bars during its opening and closing.

Outside the sash within the parts which frame the outer faces of the respective sash bars, when the sash is occupying a closed position, are inserts 12 of rubber or other suitable material. In other words, the outer 70 walls of the runways, the outer wall at the lower end of the opening 7 in the head of the frame and the weather-strip 8 are provided with these inserts, which combine or run into one another to form a united insulating packing entirely around the exterior of the sash. The inserts preferably bulge in the direction of the sash beyond the faces of the parts within which they are contained 75 so that the sash when moved outwardly will bear against the inserts and an airtight seal be thereby obtained.

The sash is moved outwardly and held tightly against the inserts by cams 13 on the jambs inside the sash. These cams when turned tighten against the side bars of the sash or preferably against wearing plates 80 15 thereon.

When the sash is in closed position bearing against the inserts it cannot be opened 90 for the reason that the opening 7 in the head of the frame or rather that portion of the opening above the lower part thereof which frames the upper sash bar is only of sufficient size to permit of the passage of 95 the sash when the sash is occupying a closed position released from the action of the cams and the U-shaped bars along the sides of the sash are occupying a position bearing against the front side walls of the runways 100 105 in which they are contained. This is the normal position of the U-shaped bars or one permitting of the opening and closing of the sash, the bars being normally but yieldingly maintained in such position by socketed spring-pressed plungers 16 inserted

in the outer walls of the runways 6 and bearing against the outer sides of the channel bars. When the sash is closed and moved outwardly by the action of the cams 5 for effecting the seal as aforesaid the plungers are displaced into their sockets, but immediately become active to throw the sash into position for opening or closing upon the release of the cams.

10 In connection with the construction and operation of the device attention is also directed to the fact that during the sliding movement of the sash it is maintained out of contact with the inserts or parts forming 15 the seal, wear only coming upon the channel bars which in this connection act as replaceable wearing parts.

Having thus fully described my invention, I claim and desire to secure by Letters Patent of the United States:

1. In a window, the combination comprising a sliding sash, means framing said sash to permit the latter to have when closed an appreciable movement of translation 25 perpendicular to the plane of the sash and having sliding movement to open only when said sash is occupying a determinate position of said translation, means for making a seal-forming joint between the sash and frame when the sash is occupying a closed 30 position and moved translatable out of said determinate position for opening, members embracing the sides of the sash and movable translatable therewith and in which 35 the sash is slidable, means engaging said members for normally holding said sash in said determinate position for opening the sash and for breaking said joint, and other positively acting means whereby said sash 40 when closed may be moved and held out of said determinate position for opening and in position to make said seal-forming joint.

2. In a window, the combination comprising a sliding sash, means framing said sash whereby it may have a sliding movement to open and whereby also the sash when closed may have an appreciable movement of translation perpendicular to the plane of the sash, said framing means bearing seal-forming parts extending around the sash and against which the sash bars are adapted to have bearing, means for holding the sash when closed against said seal-forming parts, members embracing the 50 sides of said sash and movable translatable therewith and in which the sash is slidable, and means engaging said members whereby the sash will be held out of contact with said seal-forming parts during the sliding 55 movement of the sash.

3. In a window, the combination comprising a sliding sash, means framing said sash to permit the latter to have when closed an appreciable movement of translation perpendicular to the plane of the sash and have

sliding movement to open only when said sash is occupying a predetermined position, said framing means having seal-forming parts extending around the sash and against which the sash bars are adapted to have bearing, members embracing the sides of said sash and movable translatable therewith and in which members the sash is slideable, releasable means for holding the sash when closed against said seal-forming parts, and means engaging said sash-embracing members for holding said sash out of contact with said seal-forming parts and in the predetermined position for opening as aforesaid.

4. In a window, the combination with a sliding sash, of means framing said sash whereby it may have a sliding movement to open and close and whereby the sash may have an appreciable movement of translation, said framing means bearing seal-forming parts extending around the outside of the sash and against which the outside may be pressed to seal the joint thereat, bearing means within the framing means and presenting bearing strips to the outside walls of the sash and movable translatable therewith, springs acting against said bearing means and serving normally to press the latter toward the sash to force the latter away from said seal-forming parts, and one or more cam devices engaging the inside walls of the sash and operable at will to press the sash against said seal-forming parts to close the joint.

5. In a window, the combination with a sliding sash, of means framing said sash whereby it may have a sliding movement to open and close and whereby the sash may have a movement of translation, said framing means bearing seal-forming parts extending around the sash and against which the sash may be pressed to seal the joint thereat, bearing means presenting bearing surfaces to the sash and movable translatable therewith, means acting through said bearing means and serving normally to force said sash away from said seal-forming parts, and means acting in an opposite direction and operable at will to press the sash against said seal-forming parts to close the joint.

6. In a window, the combination with a sliding sash, of means framing said sash and presenting channels or runways with in which the sash may be opened or closed, seal-forming parts presented by said framing means to the outside of the sash and extending around the sash, said runways being wider than the sash to permit the sash to be moved laterally against said seal-forming parts to seal the joint thereat, or away from the same to permit the sash to be raised or lowered while disengaged from said seal-forming parts, devices adapted to

engage the sash for moving the same normally away from said seal-forming parts, and other devices operative at will to throw the sash laterally in the opposite direction ¹⁰ to close the joint.

7. In a window, the combination with a sash, of framing parts 1, 3, 4 and 5 in which the sash may be raised and lowered

but permitting also lateral movement of the sash, seal-forming parts 12 extending around the exterior of the sash, bearing members 10, springs 16 to force the bearing parts and sash away from the seal, and clamping devices 13 to force the sash toward the seal.

ARTHUR H. BALLARD.
